(57) **CLAIM**

The ornamental design for a portion of a display screen of a handheld device with transitional icon, as shown and described.

DESCRIPTION

FIG. 1 is a front view of a portion of a display screen of a handheld device with transitional icon in a first appearance state, shown enlarged and separately for ease of illustration; FIG. 2 is a front view thereof in a second appearance state; FIG. 3 is a front elevational view of the handheld device rotated 90 degrees relative to FIG. 1 shown in the first appearance state;

FIG. 4 is a rear elevational view of the handheld device; FIG. 5 is a left elevational view of the handheld device; FIG. 6 is a right elevational view of the handheld device; FIG. 7 is a top plan view of the handheld device; FIG. 8 is a bottom plan view of the handheld device; FIG. 9 is an enlarged view of the display including the icon in the first appearance state; and, FIG. 10 is an enlarged view of the display including the icon in the second appearance state.

The appearance of the transitional icon sequentially transitions between the states shown in FIGS. 1 and 2. The process or period in which the image transitions to another image forms no part of the claimed design.

The evenly spaced broken line showing of a handheld device, display screen, and portions thereof, form no part of the claimed design.

The dot dash lines define the boundary of the claimed design and form no part thereof.
